(57) **CLAIM**

The ornamental design for a handle for electric toothbrush as shown and described.

DESCRIPTION

1. Handle for electric toothbrush
5. Handle for electric toothbrush
- 1.1 Front Perspective view
- 1.2 Rear Perspective view
- 1.3 Front
- 1.4 Back
- 1.5 Left
- 1.6 Right
- 1.7 Top
- 1.8 Bottom
- 5.1 Front Perspective view
- 5.2 Rear Perspective view
- 5.3 Front
- 5.4 Back
- 5.5 Left
- 5.6 Right
- 5.7 Top
- 5.8 Bottom

The broken lines in the drawings illustrate portions of a handle for electric toothbrush that form no part of the
